DRINKING STRAW

Harry E. Davis, 544 Vinite St., Akron, Ohio

Filed May 28, 1963, Ser. No. 75,099

Term of patent 14 years

(Cl. D2—3)

I claim:

The ornamental design for a drinking straw, substantially as shown.
